EXPANSIBLE PLUG CLOSURE

Howard H. Armstrong, Cuyahoga Falls, Ohio, assignor to The B. F. Goodrich Company, New York, N. Y., a corporation of New York

Application August 7, 1947, Serial No. 766,999

13 Claims. (Cl. 220—24.5)

1

The invention relates to removable sealing closures for passages of containers and especially to closures for the mouths of fuel and gasoline tanks, bottles, jars and other containers for liquids, gases and other flowable materials.

Objects of the invention are to provide an improved removable closure effecting sealing between a compressible body thereof and the mouth or passage of a container; to provide for resisting axial separation of the closure from the mouth or passage in the engaged condition by a pawl-like resisting action of the compressible body, and at the same time to provide for facilitating quick removal of the closure; to provide effective locking along with quick removability; to provide for effecting sealing while avoiding suction between the compressible body and the mouth or passage; and to provide for simplicity of construction, convenience of manufacture and use, and for effectiveness of operation.

These and other objects and advantages will be apparent from the following description.

In the accompanying drawings which form a part of this specification and in which like numerals are employed to designate like parts throughout the same,

Fig. 1 is a perspective view from above of a sealing closure in the mouth of a gasoline tank and constructed in accordance with and embodying the invention, parts being broken away,

Fig. 2 is a sectional view on an enlarged scale taken along line 2—2 of Fig. 1, parts being broken away,

Fig. 3 is a front view on an enlarged scale of the closure in the disengaged or released condition, dot and dash lines showing the position of parts in the engaged condition, and parts being broken away and in section, and

Fig. 4 is a perspective front view from above on an enlarged scale of the compressible annular body of the closure, parts being broken away and in section.

In the illustrative embodiment of the invention shown in the drawings, the closure construction is associated removably with the filler pipe or mouth 11 of a gasoline tank 12 suitable for aircraft and other vehicles.

The closure includes an annular body or sealing member 13 of generally cylindrical shape as shown in Fig. 4 and of solid elastic material such, for example, as resilient rubber, natural or synthetic, or other rubber-like compositions having the characteristics of resiliency, high resistance to oil, gasoline, ether, naphtha and other like solvents and materials, impermeability to liquids

and gases, high coefficient of friction, and little or no tendency to impart odors or otherwise taint the contained material. The solid annular body 13 has an axial bore 14 of uniform diameter therein extending from the lower end face 15 and desirably therethrough to the upper end face 16 providing radially spaced inner and outer surfaces 17, 18, respectively.

There is provided on the radially outer surface 18 at least two and desirably three circumferentially extending portions 19, 20, 21 spaced-apart axially providing circumferentially extending spaces or channels 22, 23 therebetween at axially spaced regions of the body 13. The circumferential portions or ribs are of such size, shape and disposition as to be effective under compression of the body to hold against the inner face of the mouth 11 to lock the body as shown especially in Fig. 2. The locking ribs 19 and 21, and the sealing 20 rib 20 also, may be inclined as by a taper of one or both margins 19a, 20a, 21a of each rib toward the top or upper end face 16 of the annular or gasket body 13, to provide increased resistance to movement of the body outwardly of the container 25 12 by a pawl-like resisting action of the ribs, when they are pressed against the container surface, the drag on the ribs under any such tendency to movement causing them to tend to swing more nearly erect and increase the resistance in 30 the manner of a pawl or moving strut. The channels between the ribs are sufficiently wide to permit substantial flexure of the ribs.

The circumferentially continuous intervening rib 20 may be axially wider than the alternate, 35 circumferentially discontinuous locking portions or ribs 19, 21, for presenting an annular, continuous sealing face of substantial axial extent at the outer surface 18. This construction facilitates the provision of a relatively wide, fully sealed zone of the closure, when in engagement with the mouth 11, to assure fluid-tightness of the connection.

For eliminating suction action at the channels and facilitating ease of removal of the closure, the upper and lower locking elements or ribs 19, 45 21 each may have one or more open-face passages or troughs 24, 24 and 25, 25 respectively, in venting communication with the adjacent channel and a free face of the body or the space at an end of the closure for venting the channels at 50 all times. Desirably, four circumferentially spaced-apart passages are in each upper and lower rib 19, 21 dividing the latter into four locking portions and facilitate venting and interlocking 55 connecting the spaces or channels at the sides of

the sealing portion 20 with the ends of the closure. Non-suction sealing and locking action is thus provided despite the compressed and radially expanded arrangement of the body 13, thereby permitting the closure to resume readily its original non-compressed condition, as shown especially in Fig. 3, and be easily removed from the mouth of the tank by axial separating movement.

The closure has means for compressing the compressible annular body 13 axially and expanding the same radially or circumferentially. There is provided a core or sleeve member 26 of stiff material, desirably metal such, for example, as steel, aluminum, magnesium and zinc alloy, or plastic material of the desired strength. The sleeve member is disposed in the bore 14 in telescopic and backing relation to the body 13 at the inner surface 17 thereof, the tubular wall of the sleeve extending axially from the lower end face 15 and terminating desirably short of the upper end face 16 of the body. The lower end of the body is engaged and supported by a radially outward flange portion 21 of the sleeve. A center post 28 may be secured to the axial center of an axially depressed, closed, transverse web portion 29 joined circumferentially to the tubular wall of the sleeve at the upper end thereof, which post 28 extends beyond the annular body 13 and has slidably mounted thereon a top pressure plate 30 of suitable stiff material.

The pressure plate 30 may have an axially depressed, closed center portion 31 and a peripheral flange portion 32 of greater diameter than the body 13 for seating flush against the upper end face 16 and the upper surface at 33 of the mouth 11, which mouth may be radially flanged and attached at the flange to the tank as by rivets 34, 34. The pressure plate also engages and supports the compressible body 13, and at the depressed portion 31 may extend somewhat below the upper end face 16. Space at 35 between the pressure plate and the web portion 29 of the sleeve accommodates bulging radially inward of the upper part of the body 13 for the compressed condition thereof, as shown especially in Fig. 2.

A swinging lever 36 including a cam portion 37 of substantially U-shape in cross-section for embracing the upper end of the center post 28 is connected pivotally thereto by a headed cross pin 38 and cotter pin 39. A washer 40 of suitable stiff material may be slidably mounted on the center post and interposed between the pressure plate 30 and the cam portion 37 of the lever 36 for strengthening and preventing wear of the pressure plate. The cam portion is adapted to engage the washer and hence position the pressure plate, when the lever 36 is swung to its lowered position at 41, as shown by dot and dash lines in Fig. 3, for drawing the sleeve member 26 toward the pressure plate to compress axially the annular body 13.

For preventing accidental loss of the closure from the tank such as during filling the latter with gasoline, the closure may, if desired, have a spanner element 42 of suitable stiff material of sufficient length to span the mouth 11 and seat against the lower inside edge of the same, which spanner element may be attached to the sleeve member 26 at the web portion 29 as by a suitable length of chain 43 and connecting ring structure 44. The arrangement permits removal of the closure from the mouth of the tank until the end of the chain 43 is reached, when the spanner element, positioned transversely, contacts the mouth, whereby the closure is retained adjacent

the mouth for convenient replacement therein. When the spanner element is positioned axially of the mouth after disengagement of the closure, the closure may be wholly dissociated from the tank as for purposes of servicing and replacement.

The closure assembly is inserted in the mouth of the tank while the lever 36 is in its raised position at 45 and the annular body 13 is under little or no compression axially for avoiding radial bulging of the body and thus facilitating convenience of insertion. The closure is inserted until the pressure plate 30 seats firmly against the upper surface 33 of the mouth 11. As the lever 36 is swung down to its lowered position at 41, the sleeve member 26 and center post 28 are moved axially of the closure toward the pressure plate, which produces axial compression and radial expansion of the annular body 13 so that the radial outer surface 18 of the latter tends to assume an outwardly bulged configuration substantially as shown by dot and dash lines at 46 in Fig. 3, when not otherwise restrained as by the wall of the mouth 11.

Under the compression, the annular body presses resiliently and radially inward against and in sealing relation to the tubular wall of the core or sleeve member 26 including the flange 21, and may bulge radially inward at its upper region into the space at 35, as shown especially in Fig. 2. The compression of the body and the aforesaid tendency of the outer surface 18 to bulge results in bringing the ribs 19, 20, 21 axially toward one another and in flexing the same, because of their inclined construction, toward the pressure plate as hereinabove described.

The open-face passages 24, 24 and 25, 25 having venting communication with the channels 22, 23 and the spaces at the ends of the closure, eliminate suction at the channels despite the compression of the body 13 and the pressing of the ribs against the mouth 11.

Variations may be made without departing from the invention as it is defined in the following claims.

I claim:

1. A closure for the mouth of a container, said closure comprising a body of resilient material having a peripheral sealing portion for disposition against said mouth and having a locking portion at a side of said sealing portion providing a space therebetween, said space having venting communication with a face of said body, and means for distorting said body to press said sealing portion and said locking portion against said mouth.

2. A closure for the mouth of a container, said closure comprising a body of resilient material having a peripheral sealing portion for disposition against said mouth and having locking portions spaced-apart peripherally of said body at a side of said sealing portion and spaced from the latter, the spaced-apart relation of said locking portions providing venting passage through the region of said locking portions, and means for distorting said body to press said sealing portion and said locking portions against said mouth.

3. A closure for the mouth of a container, said closure comprising an annular body of resilient material having a circumferential sealing portion for disposition against a surface of said mouth and having a circumferential locking portion at each side of said sealing portion in spaced relation thereto, the space between said sealing portion and each of said locking portions having

venting passage through said locking portions, and means for compressing said body axially to press said sealing portion and said locking portions in the radial direction against said mouth.

4. A closure for the mouth of a container, said closure comprising a core for said mouth providing an annular space between said mouth and said core, an annular body of resilient material having in its relaxed condition less thickness than said space, and means for compressing said body axially and increasing its thickness radially to fill the radial dimension of said space, and said body comprising a circumferential sealing portion and a locking portion at a side of said sealing portion with a pocket therebetween, said pocket being in venting communication with a face of said body.

5. A closure for the mouth of a container, said closure comprising a core for said mouth providing an annular space between said mouth and said core, an annular body of resilient material having in its relaxed condition less thickness than said space, and means for compressing said body axially and increasing its thickness radially to fill the radial dimension of said space, and said body comprising circumferential portions spaced-apart axially with a pocket therebetween, said pocket being in venting communication with a face of said body in the relaxed condition of said body, and one of said portions being circumferentially continuous and relatively wider than the other portion for sealing against said mouth under the compression of said body.

6. A closure for the mouth of a container, said closure comprising a body of resilient material having a circumferentially continuous sealing portion and a circumferentially discontinuous locking portion adjacent said sealing portion with a space between said portions, said space having venting communication with a face of said body, and means for compressing said body to press said portions against a container mouth.

7. A closure for the mouth of a container, said closure comprising an annular body of resilient material having a circumferentially continuous sealing portion and a circumferentially discontinuous locking portion adjacent each side of said sealing portion with spaces between said sealing portion and said locking portion, each of said spaces being in venting communication with an end of said body, and means for compressing said body axially to press said portions in the radial direction against a container mouth.

8. A closure for the mouth of a container, said closure comprising an annular body of resilient material having an axial bore extending therein from an end thereof providing inner and outer surfaces, said body having a circumferential sealing portion and locking elements of said material spaced axially from said portion on one of said surfaces, the spaces between said portion and said elements having venting passage through the region of said elements, a backing element in said bore, and means for compressing said body axially between said mouth and said backing element to press said sealing portion and said locking elements in the radial direction.

9. A closure for the mouth of a container, said closure comprising a body of resilient material having a circumferentially continuous sealing portion and a circumferentially discontinuous locking portion adjacent said sealing portion with a space between said portions, said space having venting communication with an end face of said body for preventing suction as a result of radial

distortion of said portions against said mouth, said locking portion being axially inclined for resisting movement in the direction toward the open-end of said mouth by a pawl-like action, and means for compressing said body axially to distort and press said portions in the radial direction against the container mouth.

10. A closure for the mouth of a container, said closure comprising an annular body of resilient material having an axial bore therein and circumferentially extending ribs spaced apart axially on said body with a circumferential channel therebetween, one of said ribs being of relatively greater axial extent than the other rib and presenting a circumferentially continuous sealing face for sealing and said other rib being axially inclined for resisting movement in the direction toward the open-end of said mouth by a pawl-like action when said body is compressed axially and expanded radially against said mouth, said channel being in venting communication with an end face of said body, a backing element in said bore, and means for compressing said annular body axially between said mouth and said backing element to press said ribs in the radial direction against the container mouth.

11. A sealing member for a container mouth closure, said sealing member comprising a generally cylindrical body of resilient material having a circumferentially-extending external surface between the ends thereof positionable in the container mouth, said body having a pair of ribs on said external surface distortable against the container, one of said ribs extending entirely and continuously around said body and constituting a sealing rib and the other rib extending circumferentially of said body in axially spaced-apart relation to the first rib, the space between said ribs having venting communication with one of said ends for preventing suction as a result of distortion of said ribs against the container.

12. A sealing member for a container mouth closure, said sealing member comprising an annular generally cylindrical body having inner and outer peripheral faces between end faces thereof, said body having a pair of ribs on the outer peripheral face positionable in the container mouth and distortable against the container, one of said ribs extending entirely and continuously around said body and constituting a sealing rib and the other rib extending peripherally of said body in axially spaced-apart relation to the first rib, the space between said ribs on said outer peripheral face venting communication with another of said faces of the body for preventing suction as a result of distortion of said ribs against the container.

13. A sealing member for a container mouth closure, said sealing member comprising a generally cylindrical body of resilient material having an axial passage therethrough from end to end thereof for accommodation of a manipulating member, and a circumferentially-extending external surface between said ends positionable in the container mouth, said body having a circumferentially continuous sealing rib and a circumferentially discontinuous locking rib adjacent one another on said external surface with a circumferential space between said ribs, said space having venting communication with one of the ends of the body for preventing suction as a result of radial distortion of said ribs when said body is pressed radially against the container, and

said locking rib being axially inclined for resisting movement in the direction toward the open-end of the container mouth by a pawl-like action.
